UNITED STATES PATENT OFFICE.

ISRAEL V. EDGERTON, OF CHICAGO, ILLINOIS, ASSIGNOR OF ONE-HALF TO JESSE R.
GRANT AND ONE-HALF TO V. E. GRANT, BOTH OF CHICAGO, ILLINOIS.

EGG-SHIPPING RECEPTACLE.

Application filed October 26, 1921. Serial No. 510,622.

To all whom it may concern:

Be it known that I, ISRAEL V. EDGERTON, a citizen of the United States, residing at Chicago, in the county of Cook and State of Illinois, have invented certain new and useful Improvements in Egg-Shipping Receptacles, of which the following is a specification.

This invention relates to packing receptacles used in the storage and shipment of eggs, and is concerned particularly with the provision in such receptacles of an improved spacing and cushioning construction associated with the interior egg-containing cellular structures commonly employed.

The main and primary object of the present invention is the provision, with a plurality of superposed tiers of horizontally arranged cells having vertical side walls, of horizontally positioned separating sheets interposed between the tiers and provided with means serving both to prevent horizontal shifting of the tiers relative to the sheets with which they are in contact and to form a cushion for absorbing vertical shocks which would otherwise be transmitted undiminished from said sheets to the eggs contained within said tiers.

Another important object of the invention is the provision of a horizontal separating sheet such as described which may be manufactured at a low cost and used in connection with the ordinary cellular filler whereby to effect a substantial pecuniary savings by cutting down the percentage of eggs which have heretofore been lost through breakage when the ordinary plain separating sheet was employed.

Still another object of the invention is the provision of a separating sheet such as described which is not characterized by a complicated construction but is, on the other hand, as easy to use in practice as the ordinary inefficient separating sheet that it is designed to replace.

Other objects and advantages of the invention which are not specifically set forth will be obvious upon a full understanding of the construction, operation and disposition of the device as obtained from the disclosure

in the following specification and accompanying sheet of drawings.

While this disclosure is confined to one preferred structural embodiment of the invention and to two slightly modified forms thereof, it is to be understood that the same is presented here entirely for the purpose of illustration, and is not intended to be construed as limiting the invention as defined by the claims short of its true and most comprehensive scope in the art.

In the drawings,

Fig. 1 is a fragmentary plan view of a case containing the interior cellular structure with which this invention is concerned;

Fig. 2 is a vertical section taken on the line 2—2 of Fig. 1;

Fig. 3 is an enlarged view of a portion of Fig. 2; and

Figs. 4, and 5 are similar views to Fig. 70 3 but show slightly modified forms of the separating sheet.

In these views the numeral 10 is used to indicate the wooden egg case of well known construction in which is positioned a plurality of superposed tiers 11 in cellular structures which are commonly known in the art as fillers. Each of these fillers is constructed of a plurality of spaced parallel strips 12 of straw board or similar material which are positioned on edge and intersected perpendicularly by other similarly arranged strips 12 whereby to form a plurality of square horizontally arranged egg-receiving cells 13 having vertical side walls. It will be noted from the drawings that the length of each of the strips 12 is equal to either of the horizontal interior measurements of the compartment of the case 10 in which the fillers seat, and that narrow end cells 14 are formed in each filler about the periphery thereof between the sides of the case and the egg cells bordering thereon because of the fact that the side strips necessarily intersect the other strips a short distance from their ends and leave fin-like extensions 15 which form the vertical portions between the said narrow end cells.

Heretofore it has been the practice to insert between each two of the fillers above 100

described a plain square sheet of straw board. These sheets are of such size as to fit snugly within the compartment of the case, and serve to support the layers of eggs 5 which are held in spaced lateral relation by the vertical side walls of the fillers.

In the absence of a better separating means which may be manufactured without a too greatly increased cost and which can 10 be used in practice without slowing up the work of packing, the plain sheet described in the paragraph above has been used to a great extent, but the loss occurring through breakage of eggs in transit with this construction is quite large. This is due to the 15 fact that when the egg crate receives a side or end jolt of any kind, such as the shocks which are constantly occurring in a railway car or truck during transit, the eggs in each 20 layer tend to shift laterally in the fillers with the momentum of their combined weights, and, since there is no connection between the fillers and separating sheets serving to anchor the former to the latter, 25 the narrow end cells 14 of the fillers are soon crushed and the eggs pounded disastrously against the hard side of the crate to which they are thereby exposed.

In order to obviate the occurrence of just 30 such breakage as above described, the separating means which forms the essence of the present invention has been developed. This separating means, which serves both as a cushion to protect the eggs against vertically transmitted jars and as a shock-absorber to protect the eggs against horizontally transmitted jolts, is inexpensively 35 formed as a square sheet 16 of stiff straw board or the like, on the upper surface of 40 which is provided parallel strips 17 of straw board having flat under layers secured substantially throughout their areas to the sheet and transversely corrugated upper layers secured in their depressions to the under 45 layers.

As shown in Fig. 1, these strips are spaced from each other only a sufficient distance to permit the seating between each two of one of the partitions strips 12 of the filler there- 50 above, and the two end strips are spaced inwardly from the margins of the sheet. The strips 12 of the filler at right angles to the strips 12 seated between the corrugated strips rest in the depressions 18 be- 55 tween adjacent ribs 19 of the corrugations.

It will be obvious from this arrangement that a secure locking is had between each separating sheet 16 and the filler 11 resting thereon. Because of this interlocking 60 of the sheet 16 with each of the vertical side walls of the filler thereabove, any tendency of the filler to shift horizontally, due to the weight of the eggs contained therein, is equally distributed and absorbed over 65 the surface of the sheet, and the danger of

crushing the narrow end cells 14 which space the eggs from the sides of the crate 10, is entirely obviated.

While these strips of corrugations are preferably formed on one face of the sheet 70 16 by the securement of corrugated strips thereto, it is within the contemplation of this invention to provide these corrugations integrally with the sheet by stamping them in the surface thereof, as shown in Fig. 5. 75 It is also within the contemplation of this invention to provide the corrugations both upon the upper and lower surfaces of the sheet as shown in Figs. 4 and 5, whereby each sheet will have both the fillers above and below interlocked therewith. Although the corrugations referred to have been described and illustrated as being formed in strips, it should be understood that, if found desirable in some constructions, the strips of corrugations may terminate abruptly at intervals corresponding to the positions of the partition strips 15 across their paths whereupon the corrugated surface of the sheet 80 will consist of a plurality of closely arranged corrugated squares with spacing for the bottom edges of the partitions 12 between the adjacent sides thereof. It should 85 be further understood that these corrugations, while having been described and illustrated as parallel furrows and ridges, may be formed in any shape or manner in so far as the results given by such formations are substantially identical with the results derived when the parallel furrows and ridges 90 100 are employed.

I claim:

1. The combination with a filler member containing a plurality of open ended cells having vertical side walls, of a sheet for supporting the filler member and the eggs contained within the cells thereof, said sheet being provided on one surface with closely placed parallel strips of transversely running corrugations which cover substantially 110 all of the area of said surface within the cells in the filler member and are spaced inwardly from the margin of the sheet along the outer sides of the two end strips.

2. The combination with a filler member containing a plurality of open ended cells having vertical side walls, of a sheet for supporting the filler member and the eggs contained within the cells thereof, said sheet being smooth on one surface and being provided on the other surface with closely placed parallel strips having thereon similar shaped strips of transversely running corrugations which cover substantially all 120 of the area of said surface within the cells of the filler and are spaced inwardly from the margin of the sheet along the ends of all the strips and the outer sides of the two end strips.

3. A sheet of the character described, pro-

vided on one surface with closely arranged parallel strips of straw board having flat under layers secured substantially throughout their areas to the sheet and transversely

⁵ corrugated upper layers secured in their depressions to the under layers, the outer sides of the two end strips being spaced inwardly from the adjacent margins of the sheet,

whereby only that portion of the sheet within such margins is reinforced in the 10 plane thereof by the flat under layers of the strips.

In testimony whereof I have hereunto signed my name.

ISRAEL V. EDGERTON.
